UNITED STATES PATENT OFFICE

JAMES M. WEAVER, OF LOS ANGELES, CALIFORNIA

LOCK

Application filed December 21, 1925. Serial No. 76,582.

This invention has to do generally with locks, and is particularly well adapted for embodiment in locks wherein the bolt and bolt throwing spindle are of cylindrical form whereby only two axially perpendicular holes need be bored in a given door to prepare it for installation of the lock; in contradistinction to usual locks which, due to their configuration, necessitate considerable chiseling and cutting of the door. However, it will be understood that the invention, considered in its broader aspects, is not limited to embodiment in a lock having these particular characteristics. For instance, the bolt assembly shown may be used in combination with a type of throwing spindle other than that illustrated; or vice versa.

It is among the general objects of the invention to provide a lock that is simple and sturdy, one which is unfailing in action, and one which may be installed with minimum effort and with minimum mutilation of the door.

A special feature of the invention resides in the provision of means within the spindle for locking the bolt in extended position. To accomplish this I have utilized a spindle of tubular form, the bolt locking member being movable longitudinally through the spindle bore, though it lies within the scope of the invention to provide a locking member within the bore which is movable to and from locking position by movement other than longitudinally.

The locking member is adapted to be controlled in its movement by means provided at the ends of the spindle, the means preferably, though not necessarily, being key-controlled. As will be made apparent in the detailed specification, the throwing of the locking member may be accomplished either by rotation or longitudinal movement of the externally accessible portion of the actuating means, and, therefore, I do not wish my broader claims to be construed as being limited to any particular type of actuating means.

Preferably, I utilize spring means for holding the locking member normally in retracted position, and in certain embodiments

of the invention I employ automatically acting latch means for holding the locking member in extended position against the action of the spring, the latch means being releasable from either end of the bolt throwing spindle. 55

Other novel features and objects of the invention will be made apparent in the following detailed description, reference being had to the accompanying drawings, in which:

Fig. 1 is a fragmentary elevation showing 60 a door and casing equipped with my lock;

Fig. 2 is an enlarged section on line 2—2 of Fig. 1;

Fig. 3 is a section on line 3—3 of Fig. 2;

Fig. 4 is a fragmentary side elevation of 65 the bolt housing as viewed from the position of line 4—4 in Fig. 2;

Fig. 5 is a section on line 5—5 of Fig. 2;

Fig. 6 is a section on line 6—6 of Fig. 2;

Fig. 7 is a view similar to Fig. 6 but showing the bolt manually thrust to the position it is put when assembly or disassembly of the bolt and throwing spindle is being accomplished; 70

Fig. 8 is a view similar to Fig. 6 but showing the bolt thrown to retracted position by rotation of the throwing spindle; 75

Fig. 9 is a view similar to Fig. 6 but showing a slightly modified type of bolt throwing spindle; 80

Fig. 10 is a detached section on line 10—10 of Fig. 2;

Fig. 11 is a section on line 11—11 of Fig. 10;

Fig. 12 is a section on line 12—12 of Fig. 85 10;

Fig. 13 is a section on line 13—13 of Fig. 10;

Fig. 14 is a fragmentary view similar in part to Fig. 10, but showing the locking member thrown to extended or operative position; 90

Fig. 14^a is a fragmentary plan view of Fig. 14 as viewed from position of line 14^a—14^a;

Fig. 15 is a vertical section through a bolt throwing spindle having a somewhat different type of lock member actuating means and key-controlled mechanism therefor; 95

Fig. 16 is a section on line 16—16 of Fig. 15;

Fig. 17 is a plan view of the tubular plung- 100

er shown in Fig. 16 as viewed from line 17—17 in that figure;

Fig. 18 is a section on line 18—18 of Fig. 17;

5 Fig. 19 is a view similar to Fig. 15 but showing the bolt locking member thrust to locking position, with the key as yet unremoved from the lock;

Fig. 20 is a section on line 20—20 of Fig. 19;

10 Fig. 21 is a view similar to Fig. 19 but showing the condition of the lock after the key has been removed therefrom;

15 Fig. 22 is a view of the lock shown in Fig. 15, adjusted in a manner whereby the locking member may be moved to operative position by manipulation of a sleeve or bushing about the cylinder without the application of a key;

20 Fig. 23 is a view of the mechanism shown in Fig. 16 but showing it in a different position;

Fig. 24 is a fragmentary view similar, in part, to Fig. 15, but showing a modified type of latching and release mechanism; and

25 Fig. 25 is a section on line 25—25 of Fig. 24.

At the outset, I wish to make the reservation that while I will describe the precise make-up of the lock with a degree of particularity, it will be understood the invention, 30 considered in its broader aspects, is not limited to certain of these particularities. It will also be understood that while, for convenience, I have specified particular types of locking member control means on the 35 throwing spindle at the outer side of the door and different types of control means on the end of the spindle at the inner side of the door, these specifications are not to be considered as limitative; for in certain situations 40 it may be desirable to provide control means of any of the illustrated types on both sides of the door or to eliminate the control means entirely at one side of the door. Furthermore, it is to be understood that certain of 45 my claims are drawn to certain features of the bolt assembly or to the spindle construction and are not limited to the inclusion of any type of locking means.

In the drawings, numeral 10 designates a 50 fragment of a door which is adapted to close against stationary door casing 11, there being a catch plate 13 of any suitable design mounted on the inner face of the casing and adapted to take the bolt of my lock.

55 In preparing the door for installation of my lock, there are bored two axially perpendicular and intersecting holes 14 and 15^a, hole 14 being bored from the edge of the door, and hole 15^a being bored through the door from 60 side face to side face.

I will first describe the bolt assembly A. This assembly is made up of a tubular sleeve or housing 15 which has at its outer end a flange 16 which forms a face plate adapted to 65 engage the edge of the door, being secured to

said edge by screws 17. Bolt 18 is cylindrical throughout the major portion of its extent and is adapted to slide longitudinally through housing 15. The bolt is made up of a nose piece 19 preferably having a flat face 70 20 which is adapted to engage the flat face 21, formed at the mouth of keeper 15 by flange 21^a, to hold the bolt from rotation within the keeper. Fitted tightly over the reduced portion 22 of nose piece 19 is a tube 23 which has 75 longitudinally extending and diametrically opposed arms 24. The ends of these extensions are turned inwardly into end opposition to provide angular fingers or hooks 25, the ends of the hooks being spaced apart as clearly shown in Fig. 6 to allow the passage therebetween of a member to be hereinafter described. The ends of arms 24 are of reduced width, as clearly shown in Fig. 2, to provide end shoulders 26.

80 The inner end of nose piece 19 is recessed at 27 to take one end of spring 28, and an abutment plate 29 (Figs. 3 and 6) is attached to said keeper and extends across the bore thereof; spring 28 acting between abutment 90 29 and nose piece 19 in a manner normally to thrust the bolt to extended position, as in Figs. 2 and 6. Plate 29 is of such width that it is taken between arms 24 so it will not form an obstruction against the stroking of the 95 bolt. When the bolt and its housing are disassembled from the throwing spindle, hooks 25 engage the abutment plate to limit the movement of the bolt in its spring-urged direction through the housing 15, the bolt and 100 housing thus being maintained in assembly. Furthermore, when the bolt is moved against the action of the spring to such a position that plate 29 extends between arms 24, said plate and arms coact in a manner to prevent positively other than a very limited amount of relative rotation between the bolt and 105 housing.

110 While any suitable means may be employed for detachably holding abutment 29 in position, the illustrated type of attachment is preferable and is the subject matter of certain claims of a patent granted to me on mortise catches, No. 1,106,760, August 11, 1914. One end of plate 29 is provided with a 115 central projection 30, while the opposite end has furcations 31. Furcations 31 are adapted to extend through suitable apertures in housing 15, while projection 30 extends through an opening 32 in the housing. Adjacent to opening 32 is a tongue 33 which is first pressed outwardly to allow projection 30 to be inserted through said opening 32 from within the tube (plate 29 having been 120 thrust longitudinally through the tube in canted position) and then is pressed inwardly to the normal position shown to hold projection 30 and hence plate 29 in place. It will be seen that assembly of the bolt and housing 125 may be readily and easily made.

At the left of abutment 29, as viewed in Fig. 6, the opposite walls of housing 15 are apertured at 34, said apertures being in line with holes 15^a when housing 15 is in place within bore 15^a. Apertures 34 and bores 15^a are of sufficient diameter to admit the passage of bolt throwing spindle 35 therethrough, ample clearance being left to insure that all elements on the peripheral face of the spindle may pass freely through said apertures and bores. However, the spindle may be considered as having spaced bearing in the wall of housing 15, since the clearances and thickness dimensions of the tubes are exaggerated in the drawings in order to avoid confusion. 70 75 80

Intermediate its ends, tubular spindle 35 is cut away or notched at 36 sufficiently to accommodate hooks 25, there being left only a small section 37 of the spindle as a connecting bar between the two spindle ends. Connecting portion 37 may be considered as the throwing bar of the spindle. With the bar thus formed, it will be seen that when the spindle is rotated, the diameter of the path of circumferential movement of the bar is no greater than that of the spindle itself, a feature of decided advantage since it holds the over-all diameter of the assembly to a minimum. 85 90 95

After the bolt assembly has been positioned within the door, bolt 18 is manually thrust to the left, as shown in Fig. 7, until hooks 25 clear apertures 34. Spindle 35 is then thrust longitudinally through bores 15^a and apertures 34 until opening 36 is in line with hooks 25. Thereupon manual pressure is relieved from the bolt, spring 28 acting to throw the bolt to the right and into the position of Fig. 6; this longitudinal movement of the bolt being limited by the engagement of hooks 25 with bars 37. As the defining edges 36^{''} of notch 36 form shoulders which are normal to the spindle axis and the tongues 25 are of substantially the same width as the notch, shoulders 36^{''} and the opposing shoulders 25^{''} on tongues 25 cooperate to hold the spindle against subsequent appreciable movement in the direction of its axis. Since bar 37 is radially spaced or offset from the axis of rotation of spindle 35, angular movement of said spindle from the position of Fig. 6 tends to retract the bolt against the action of spring 28 (Fig. 8) to withdraw nose 19 from catch-plate 13. 100 105 110 115

It will be noted that spindles 35 may be considered broadly as extending through the bolt and beyond opposite sides thereof, for it has been made apparent that arms 24 and hooks 25 may be considered a part of the bolt and they, in effect, define a hole through the bolt and taking the spindle. 120 125

Preferably, there are provided on the peripheral face of spindle 35, at opposite sides of opening 36, lugs or shoulders 38. These

lugs may each be formed by pressing a tongue of the metal outwardly and then bending it upon itself, as clearly shown in Fig. 2. Lugs 38 are so located that they contact with shoulders 26 when the bolt is in full retracted position, and by this coaction between lugs and shoulders, further angular movement of the spindle in the given direction is prevented; otherwise, angular movement of the spindle might be continued with the result that bar 37 would be returned to normal position and spring 28 would extend the bolt before such extension was intended. When spindle 35 is subsequently released, spring 28 extends the bolt, hooks 25 acting against bar 37 to return the spindle to normal. 75 80

In certain instances, it is desirable that the lock be used as a night latch, that is, it is to remain inoperative for protracted periods and only thrown into operation during certain hours. When the lock is to have this capability of being maintained in inoperative position, it may be made in accordance with the modification shown in Fig. 9. In this modification lugs 38 are omitted from spindle 35^b so said spindle may be rotated through 360°. By rotating the spindle 180° from its normal position (that is, with the bolt fully extended,) the bolt is fully retracted to the position of Fig. 9, and when the operator's hand is released from the throwing spindle, throwing bar 37^a serves to maintain the bolt in retracted position, since said bar is then in direct line with the longitudinal axis of the bolt. Bar 37^a may be slightly flattened at 37^b where it is engaged by hooks 25, in order that there may be no likelihood of the throwing spindle being jarred or otherwise accidentally returned to normal and bolt 18 consequently being returned to extended position under the action of spring 28. However, when it is desired to extend the bolt, it is only necessary that the operator rotate spindle 35^b slightly until bar 37^a is out of line with the longitudinal axis of the bolt, whereupon spring 28 is free to extend the bolt, hooks 25 acting against bar 37^a to return the throwing spindle to normal. 90 95 100 105 110

While any suitable type of escutcheon plate or knobs may be used in connection with my lock, I have shown preferred equipment in Fig. 2. Escutcheon plates 40 and 41 are secured to the end and outer faces, respectively, of the door by screws 42; and these plates have, respectively, bosses 43 and 44. These bosses are alike except that the one on the outer face of the door is provided with a tubular extension 44^a. Spindle 35 is threaded at 45 to take the hubs 46 of knobs 47. Set screws 48 in hubs 46 are adapted to hold the knobs in adjusted position along the spindle. Before spindle 35 is thrust into assembly with bolt mechanism A, the knob which is to be at the outside of the door is threaded on the spindle and screws 48 are set. These screws 115 120 125 130

are so located that when the spindle is fully assembled with the bolt mechanism, they will lie within tubular extension 44, this extension then preventing the screws from being removed, either through accident or malicious intent. The knob on the inner face of the door is then threaded on the spindle and set by its screws 48. A friction tight keeper ring 49 is then moved along the hub of the inner knob and over its set screws to prevent them from backing out.

I will now describe the releasable means for locking bolt 18 in extended position. Generally, this comprises a member provided with in spindle 35 which is movable to and from a position behind hooks 25 (and hence, in effect behind bolt 18) when the bolt is in extended position. It lies within the scope of my broader claims to provide a locking member which is movable in any desired manner into its locking position, but as a preferred type of locking member I have illustrated a plunger 50 which is mounted for longitudinal reciprocation within the bore of spindle 35, I have illustrated spring means for maintaining this locking member normally in retracted or inoperative position, and I have shown several different types of actuating and control means whereby the locking member is moved to extended or operative position. It will be understood that my claims, except when they expressly so specify, are not limited to any particular type of means for shifting the locking member. It will also be understood that the several types of locking member actuating means need not be combined in the precise manner shown. For instance, both ends of the locking spindle may be equipped with the same type of actuating members, or only one end of the spindle may be provided with an actuating member.

In order that certain auxiliary mechanism may be more easily applied to the locking member, I prefer to make this member in the form of a tubular plunger, but it will be understood that the invention, considered in its broader aspects, is not limited to a plunger of this type.

I will first describe the locking member shown in Figs. 2 to 14, inclusive, this type of mechanism being an extremely simple one and consequently particularly well adapted for use in comparatively cheap installations. The locking member is thrown to extended or operative position by rotation of keys provided at opposite ends of the throwing spindle, the key on the outside of the door preferably, of course, being a removable one. Extending from side to side of spindle 35 are spaced pins 51, these pins extending through limit slots 52 in member 50. The pins 51 thus serve to hold member 50 against rotation and limit the retractive movement of the locking member, spring 53 being interposed between pins 51 and abutment 54 secured within tube

50 serving to hold member 50 normally and yieldingly in retracted position. When thus retracted, the end 55 of tube 50 is out of line with hooks 25, these hooks then being capable of reciprocation with bolt 18 to allow said bolt to be moved from extended to retracted position or vice versa. It is desirable that tube 50 have a fairly close fit within spindle 35, for obvious reasons, and, therefore, it is necessary that where end 55 is adapted to be projected across opening 36 that said end be cut back as at (Fig. 2) in order to clear hooks 25. It will be evident that when member 50 is moved against the action of spring 53, by means to be described immediately, to bring end 55 behind hooks 25 that bolt 18 may not thereafter be moved to retracted position nor may spindle 35 be rotated. The end of member 50 is inclined as at 57, the end 58 of an actuating member 59 being complementarily inclined and, when member 50 is in retracted position, cam faces 57 and 58 are in substantially full engagement, as shown in Fig. 10. Member 59 is in the form of a short, tubular cylinder, its end 60 being closed except for apertures 61 which are adapted to take the end projections 62 on key 63. Actuating cam 59 is confined between member 50 and cylinder 64, the latter being fixed rigidly within the bore of spindle 35 by any suitable means, as, for instance, brazing, and having the usual wards 65.

By inserting a proper key 63 through keyway 66 of cylinder 64 until projections 62 extend through apertures 61, and then turning the key either to the right or left, actuating cam 59 is rotated and acts against inclined cam face 57 on member 50 to thrust said member to the right (as viewed in Fig. 10) against the action of spring 53 and into the position of Fig. 14. This movement of member 50 projects end 55 across opening 36 and back of hooks 25, thereby preventing subsequent rotation of spindle 35 and retractive movement of hooks 25 and bolt 18.

By rotating the key through 180° the points of cams 57 and 58 are brought into opposition as shown in Fig. 14, so, when key 63 is subsequently removed, member 50 will be maintained in its locking position against the action of spring 53. Preferably, the point of one cam is adapted to seat in a recess in the point of the other cam to insure that members 50 and 59 be not accidentally returned to normal. For instance, the slightly rounded end 58a of cam 58 may seat in recess 57a of cam 57 (Fig. 14a).

When the door is to be unlocked, key 63 is reinserted and turned through 180° in either direction, this movement returning actuating member 59 to normal position as shown in Fig. 10, and allowing spring 53 to return member 50 to retracted position and out of the path of the bolt hooks.

In order that member 50 may be actuated

from the other end of spindle 35, I provide it with an internal stem or rod 67 which is adapted to extend through spindle 35 and through cap 68 secured at the inner end of the 5 spindle. Exteriorly of cap 68, rod 67 is provided with a key or knob 69. It will be seen that member 50 may be thrown to and from locking position by rotation of key 69 in a manner exactly similar to that described 10 in connection with its operation by key 63. Of course, the locking member may be thrown to extended position from either end of the spindle and released for retraction by spring 53 by proper movement of the key 15 at the opposite end of the spindle. It will be seen that due to the spacing of the ends of hooks 25, as previously described, rod 67 does not interfere with the assembly or disassembly of the spindle and the bolt mechanism; for referring to Figs. 6 and 7, it will be seen that the bolt may pass to and fro from limit to limit without causing hooks 20 25 to engage rod 67.

I will now describe a locking mechanism 25 adapted particularly for use where a pin-tumbler lock cylinder is to be used, though not limited to such use. As will hereinafter be made apparent, the lock cylinder may be employed as the actuating member for moving 30 the locking member to extended or operative position, a longitudinal thrust being exerted upon said cylinder for so moving the locking member. According to the type of lock employed, as will hereinafter be made evident, 35 it may or may not require the application of a key to secure such endwise movement of the lock cylinder. But in any event it requires the application of the key to the cylinder before the locking member may be returned 40 from extended to retracted position. The means for throwing the locking member to extended position from the opposite end of the spindle may also be of the push and pull type, and the means at said opposite end of 45 the spindle for releasing the locking member so its retracting spring may function, may be of the twist or reciprocatory type.

I prefer to provide automatically latching means for releasably holding the locking 50 member in extended or operative position, and a part of this latching mechanism may be employed as a part of the means for throwing the locking member to extended position from the end of the spindle which is opposite to the end equipped with the pin tumbler lock.

Referring now to Figs. 15 to 21, inclusive, 55 I have shown an assembly similar to that previously described as regards bolt assembly A and spindle 35, except that the spindle 35^a shown in these figures is cut somewhat shorter at one end. Locking member 50^a is generally similar to locking member 50, having the same type of pin and slot connection 51^a, 52^a; 60 cut off end 55^a, and spring 53^a acting between

pins 51^a and closed end 59^a and adapted normally and yieldingly to maintain locking member 50^a in retracted position.

Extending through the end 59^a and the bore of member 50^a is a latch rod 67^a. A collar 70 on rod 67^a engages the outer face of end 59^a and the end 71 of rod 67^a beyond this collar is of polygonal cross-section. Knob 72 includes a body member 73 having a hub 74 which is threaded on spindle 35^a at 45^a and set in position by screws 48^a. Body 73 has a bore 75 and a key 76. Bushing 77 is mounted in bore 75 and has a key-way 78 coacting with key 76 to prevent relative rotation between body 73 and bushing 77. In the lock here shown, a set screw 79 is threaded through body 73 into bushing 77 to prevent relative longitudinal movement between the bushing and body member. However, when the lock is adapted to be actuated in a manner somewhat different from that now to be described, screw 79 is removed in order to allow bushing 77 to have longitudinal movement through bore 75, the spline connection between bushing and body member still acting 80 to prevent relative rotation. When the bushing is thus adapted to have longitudinal movement, spring 80, which is preferably of the conical, telescoping type, between said bushing and the inner end wall of bore 75 85 acts yieldingly to hold said bushing against end flange 81 of knob sleeve 82, the latter being removably secured to body 73 by screw 83 and having a knurled hand-grip 84.

However, when the lock is to be operated in the manner now to be described, set screw 79 holds the bushing rigidly against longitudinal movement and spring 80 has no function. Bushing 77 carries the usual tumblers 85 which are normally urged by springs 86 across the parting line between bushing 77 and cylinder C to prevent relative rotation and longitudinal movement between said bushing and cylinder. Usual key actuated pins 87 in cylinder C limit the downward 90 movement of bushing pins 85. The end of cylinder C is provided with a socket piece 88 having a socket 89 complementarily in cross section to that of rod end 71, and it may be stated at this time that the relative longitudinal movement between socket 88 and end 71 is definitely limited so that said end never becomes entirely disengaged from the socket piece. Due to the polygonal cross section characteristics of end 71 and socket 89, cylinder C and rod 67^a are held against relative rotation but are capable of relative longitudinal movement.

Latch rod 67^a terminates in a hook 90. This hook is adapted to engage a keeper 91 125 when member 50^a is thrust to extended position in the manner to be described, and this engagement serves to maintain member 50^a in extended position. Now I have shown keeper 91 as being mounted on a movable 130

plunger 92 which will later be described in detail, but for the purposes of describing the action of the locking mechanism as brought about by actuation of the pin tumbler lock, keeper 91 may be considered as stationary with respect to spindle 35^a, and certain of my claims are of such breadth that they contemplate and cover such a rigid mounting of lug 91.

When the door is to be locked, key K is thrust into cylinder C to clear tumbler pins 85. Then the cylinder is thrust forwardly into the position of Fig. 19, the endwise movement of the cylinder causing coincident endwise movement of latch rod 67^a and locking member 50^a. Rod 67^a has sufficient inherent spring to allow its terminal hook 90 to hook over lug 91, the latch connection between said rod and keeper lug serving to hold member 50^a in extended position across hooks 25 against the action of spring 53^a when cylinder C is subsequently moved to the left, as in Fig. 22, by subsequent withdrawal of the key. Of course, as soon as the cylinder is returned to the normal position shown in Fig. 21, key K may be removed since tumbler pins 85 and 87 are then in line. With the key thus removed, it will be seen that cylinder C is locked against both rotation and endwise movement, and that rod 67^a holds member 50^a in extended or operative locking position.

When the door is to be unlocked, key K is reinserted in the cylinder, clearing pins 85, 35 and rotated either in clockwise or counter-clockwise direction. Due to the connection between socket piece 88 and the square end 71 of rod 67^a, rotation of cylinder C causes coincident rotation of rod 67^a, this movement of the rod rotating hook 90 angularly clear of keeper lug 91. Thereupon, spring 53^a acts immediately against the closed end 59^a of member 50^a and returns said locking member 50^a to retracted position. End 55^a thus being cleared from the path of hooks 25, bolt 18 may subsequently be retracted by rotation of spindle 35^a.

In certain instances it is desirable that the operator be able to lock the door without application of his key. Where such a condition is desirable, set screw 79 is removed so bushing 77 is capable of longitudinal movement within body 73, though held against rotation with respect to said body by the previously described spline connection therebetween. Spring 80 then acts normally and yieldingly to maintain bushing 77 and hence cylinder C in the position of Fig. 15. When the door is to be locked, manual pressure is exerted against the end of either cylinder C or of the bushing, and the bushing and cylinder assembly being moved as one to the right against the action of spring 80 (Fig. 22) to project locking member 50^a into locking position. When the manual pres-

sure is relieved from the bushing or cylinder, spring 80 returns the bushing and cylinder assembly to the position of Fig. 15, latch hook 90 having engaged keeper 91, in the meantime, to hold member 50^a in locking position. Hook 90 is released from keeper 91 by application of the key to cylinder C and rotation thereof, as previously described.

I will now describe the preferred type of means for moving member 50^a to latching position from the other end of spindle 35^a, and for releasing the locking member latch from said opposite end of the spindle, irrespective of which locking mechanism has been actuated to throw member 50^a to locking position. Tubular plunger 92 is mounted for longitudinal reciprocation within the bore of spindle 35^a and has an operating knob 94 on its outer extremity 95, which extremity projects well beyond the end of spindle 35^a. A positioning pin 96 is secured to spindle 35^a and extends across the bore thereof. Plunger 92 has diametrically opposed slots 97 through which pin 96 extends, these slots each having a reduced portion 98 at one end and an enlarged portion 99 at the other end, a cam face 100 extending between portions 98 and 99. The pin 96 is, of course, adapted to limit the longitudinal movement of plunger 92 with respect to spindle 35^a, and spring 101 is interposed between the end flange 102 on the plunger and an abutment plate 103 secured to spindle 35^a. This spring normally acts against plunger 92 to retain it yieldingly at the limit of its movement to the right as viewed in Fig. 16, in which position pin 96 is seated within the restricted portions 98 of slots 97 to hold the plunger against rotation with respect to the spindle. Keeper lug 91 extends inwardly from the walls of tubular plunger 92, and is longitudinally spaced from end flange 102. When member 50^a is in retracted position, hook 90 is disposed between lug 91 and flange 102. Spring 101 is of considerably greater effective strength than spring 53^a so, when member 50^a is projected to locking position, as previously described, and hook 90 is sprung over keeper 91, spring 101 is competent to hold rod 67^a and member 50^a to the right against the action of spring 53^a. Since plunger 92 is now held from rotation due to the coaction of pin 96 with the restricted portions 98 of slots 97, when rod 67^a is subsequently rotated by actuation of key K, there is no danger of the frictional engagement between hook 90 and keeper 91 setting up coincident rotation of plunger 92, and, therefore, it is assured that such rotation of rod 67^a will clear hook 90 from keeper 91.

Should member 50^a be in operative locking position with hook 90 engaging keeper lug 91 to maintain it in this position, and it be desired to release said hook from the inside of the door, manual pressure is first exerted

against knob 94 to shift plunger 92 longitudinally to the left, as viewed in Fig. 19, against the action of spring 101. Spring 53^a is then competent to withdraw member 50^a from locking position, and as soon as plunger 92 has been thrust sufficiently to bring the enlarged portions 99 of slots 97 into register with pin 96, plunger 92 is rotated to the left, as viewed in Fig. 18, by manual rotation of knob 94. This rotation of the plunger moves keeper lug 91 out of engagement with hook 90, so, when pressure is relieved from knob 94, spring 101 acts to return plunger 92 to the normal position of Fig. 16 without causing a coincident return of rod 67^a. As spring 101 thus returns the plunger 92 to the right, as viewed in Fig. 16, cam face 100 engages pin 96 so plunger 92 is rotated back to normal position as well as moving 20 longitudinally, the extent of slots 97 being sufficient to insure that cam face 100 does not rotate lug 91 beneath hook 90 at the start of the return stroke of the plunger.

Assuming that the lug is in the condition 25 of Fig. 16 and that it be desired to project member 50^a into operative locking position by manipulation of knob 94, this knob is thrust straight in, (Fig. 23) moving plunger 92 to the left, the engagement of lug 91 with hook 90 springing rod 67 to allow said hook to engage behind said lug. Then when pressure on knob 94 is relieved, spring 101 acts to return plunger 92 to its normal position, lug 91 acting against hook 90 to draw rod 30 67^a and member 50^a into locking position, it being remembered that spring 101 is of sufficiently greater strength than spring 53^a to cause such movement. The locking member 35 may subsequently be released so spring 53^a may return it to normal position by operation either of cylinder C or plunger 92, as described above. It will be noted that in this assembly rod 67^a acts both as a connector between plunger 92 and member 50^a for moving 40 said member to locking position, and as a latch member for holding the locking member in locking or extended position.

In the assembly above described, it will be seen that from the inside of the door, locking is effected by thrusting a plunger endwise and then releasing it to allow an operating spring to act indirectly against the locking member, and that unlocking is effected by thrusting inwardly against the same 55 plunger and then rotating it. I will now describe a mechanism wherein locking from the inside of the door is effected in the same manner, but unlocking from that side of the door is effected by manipulation of a second 60 plunger. For this purpose, attention is directed to Figs. 24 and 25. Plunger 92^a and keeper lug 91^a thereon, are similar to plunger 92 and lock 91, respectively, except that the slots 97^a through which the spindle carried pin 96 extends, are of uniform width

throughout so there may at no time be relative rotation between spindle 35^a and plunger 92^a. The end 105 of plunger 92^a is open so release plunger 106 may extend therethrough. Plunger 106 has slots 107 to take the pin 96, and its exposed end may carry a key or operating knob 108. The opposite end of release plunger 106 has an upturned release cam 107^a which also provides an anchor for one end of spring 109. The opposite end of this spring is secured to pin 96, the spring thus acting normally to hold plunger 106 yieldingly at the end of its stroke to the right, as viewed in Figs. 24 and 25, and as determined by the coaction of pin 96 with the end walls of slots 107.

When it is desired to lock the door from the inside, knob 94^a is thrust inwardly to carry keeper 91^a beneath hook 90, as described above in connection with Fig. 16, and then released to allow spring 101 to thrust plunger 92^a back to normal, and, through the coaction between hook 90 and lug 91^a, to draw rod 67^a and member 50^a into the position of Fig. 19. When it is desired to release member 50^a, plunger 106 is thrust inwardly, spring 109 yielding lengthwise to allow this movement, until cam 107^a engages beneath cam face 90^b on hook 90, further movement of the release plunger causing cam 107 to lift hook 90 from keeper lug 91^a, whereupon spring 53^a acts to return locking member 50^a to retracted position. As soon as manual pressure is relieved from knob 108, spring 109 returns release plunger 106 to normal position.

It will be understood the drawings and description are to be considered merely as illustrative of and not restrictive on the broader claims appended hereto, for various changes in design, structure and arrangement may be made without departing from the spirit and scope of said claims.

I claim:

1. In a lock, a bolt adapted to be reciprocated longitudinally to and from extended position, means for retracting the bolt and including a tubular rotary spindle arranged substantially axially perpendicular to the bolt and operatively connected thereto, and a locking member within and movable longitudinally through the bore of the spindle into and out of locking engagement with the bolt when said bolt is extended and adapted, when in such engagement, to hold said bolt against retractive movement, and selectively operable means at opposite ends of the spindle for moving the locking member into locking engagement.

2. In a lock that includes a bolt adapted to be moved from extended to retracted position by rotation of a tubular spindle that is operatively connected thereto, releasable means for holding said bolt against retractive movement that includes a locking member mount-

ed within the tube bore for reciprocation longitudinally into and out of locking position, spring means adapted normally to urge and hold the member out of locking position, and
5 means operable from the end of the spindle for moving said locking member into locking position against the action of said spring means.

3. In a lock that includes a bolt adapted to
10 be moved from extended to retracted position by rotation of a tubular spindle that is operatively connected thereto, releasable means for holding said bolt against retractive movement that includes a locking member mounted within the tube bore for reciprocation longitudinally into and out of locking position, spring means adapted normally to urge and hold the member out of locking position, and key-controlled means operable from the end of the spindle for moving said locking member into locking position against the action of said spring means.

4. In a lock that includes a bolt adapted to
25 be moved from extended to retracted position by rotation of a tubular spindle that is operatively connected thereto, releasable means for holding said bolt against retractive movement that includes a locking member mounted within the tube bore for reciprocation longitudinally into and out of locking position, spring means adapted normally to hold the member out of locking position, and means operable from either end of the spindle for moving said locking member into locking position against the action of said spring means.

5. In a lock that includes a bolt adapted to
40 be moved from extended to retracted position by rotation of a tubular spindle that is operatively connected thereto, releasable means for holding said bolt against retractive movement that includes a locking member mounted within the tube bore for reciprocation longitudinally into and out of locking position, spring means adapted normally to urge and hold the member out of locking position, means operable from the end of the spindle for moving said locking member into locking position against the action of said spring means, and releasable means adapted to hold said member in locking position.

6. In a lock that includes a bolt adapted to
55 be moved from extended to retracted position by rotation of a tubular spindle that is operatively connected thereto, releasable means for holding said bolt against retractive movement that includes a locking member mounted within the tube bore for reciprocation longitudinally into and out of locking position, spring means adapted normally to urge and hold the member out of locking position, means operable from the end of the spindle for moving said locking member into locking position against the action of said spring
60 means, releasable means adapted to hold said

member in locking position, and means operable from the end of the spindle adapted to be actuated to release said holding means.

7. In a lock that includes a bolt adapted to
70 be moved from extended to retracted position by rotation of a tubular spindle that is operatively connected thereto, releasable means for holding said bolt against retractive movement that includes a locking member mounted within the tube bore for reciprocation longitudinally into and out of locking position, spring means adapted normally to urge and hold the member out of locking position, means operable from the end of the spindle for moving said locking member into locking position against the action of said spring means, releasable means adapted to hold said member in locking position, and key-controlled means operable from the end of the spindle adapted to be actuated to release said holding means.

8. In a lock that includes a bolt adapted to
75 be moved from extended to retracted position by rotation of a tubular spindle that is operatively connected thereto, releasable means for holding said bolt against retractive movement that includes a locking member mounted within the tube bore for reciprocation longitudinally into and out of locking position, spring means adapted normally to urge and hold the member out of locking position, means operable from the end of the spindle for moving said locking member into locking position against the action of said spring means, and releasable means for holding the locking member in locking position and including a latch member supported by the spindle, and a latch member supported by the locking member, said latch members being adapted to engage operatively when the locking member is moved to locking position.

9. In a lock that includes a bolt adapted to
80 be moved from extended to retracted position by rotation of a tubular spindle that is operatively connected thereto, releasable means for holding said bolt against retractive movement that includes a locking member mounted within the tube bore for reciprocation longitudinally into and out of locking position, spring means adapted normally to urge and hold the member out of locking position, means operable from the end of the spindle for moving said locking member into locking position against the action of said spring means, releasable means for holding the locking member in locking position and including a latch member supported by the spindle, and a latch member supported by the locking member, said latch members being adapted to engage operatively when the locking member is moved to locking position, and means operable from the end of the spindle for disengaging said latch members.

10. In a lock that includes a bolt adapted

- to be moved from extended to retracted position by rotation of a tubular spindle that is operatively connected thereto, releasable means for holding said bolt against retractive movement that includes a locking member 5 mounted within the tube bore for reciprocation longitudinally into and out of locking position, spring means adapted normally to urge and hold the member out of locking position, means operable from the end of the 10 spindle for moving said locking member into locking position against the action of said spring means, releasable means for holding the locking member in locking position and including a latch member supported by the 15 spindle, and a latch member supported by the locking member, said latch members being adapted to engage operatively when the locking member is moved to locking position, and key-controlled means operable 20 from the end of the spindle for disengaging said latch members.
11. In combination with a door, a lock embodying a tubular bolt housing extending inwardly from the edge of the door, a bolt adapted to be reciprocated longitudinally through the housing, said housing having diametrically opposite side openings in registration with side openings extending inwardly from the side faces of the door, a tubular bolt-throwing spindle having bolt-locking means within its bore, said spindle with its locking means being movable bodily longitudinally through said side openings into operative association with the bolt both as regards 30 its bolt-throwing and bolt-locking functions, and shoulders on the spindle and bolt, which shoulders are in opposition when said spindle and bolt are in such operative association, 35 the shoulders on said spindle being normal to the spindle axis, the shoulders on the spindle and bolt thereafter cooperating to hold the spindle against appreciable movement in the direction of its axis.
- 40 12. In a lock that includes a bolt adapted to be moved from extended to retracted position by rotation of a tubular spindle that is operatively connected thereto, releasable means for holding said bolt against retractive movement that includes a locking member 45 mounted within the tube bore for reciprocation longitudinally into and out of locking position, spring means adapted normally to hold the member out of locking position, and a key-controlled lock cylinder movable bodily longitudinally in the direction of the 50 spindle axis to move the locking member into locking position against the action of said spring means.
- 55 13. In a lock that includes a bolt adapted to be reciprocated to and from extended position, means for retracting the bolt and including a tubular rotary spindle arranged substantially axially perpendicular to the bolt and operatively connected thereto, a locking member within and movable longitudinally through 60 the bore of the spindle into and out of locking engagement with the bolt when said bolt is extended and adapted, when in such engagement, to hold said bolt against effective retraction, and selectively and independently 65
- is operatively connected thereto, releasable means for holding said bolt against retractive movement that includes a locking member mounted within the tube bore for reciprocation longitudinally into and out of locking 70 position, spring means adapted normally to urge and hold the member out of locking position, an actuating member operable from the end of the spindle and movable both longitudinally and rotatably therethrough, said actuating member being movable longitudinally in one direction to move the locking member into locking position, and means adapted to hold the locking member releasably in locking position; said actuating member being thereafter rotatable to release said holding means. 75
14. In a lock that includes a bolt adapted to be moved from extended to retracted position by rotation of a tubular spindle that 80 is operatively connected thereto, releasable means for holding said bolt against retractive movement that includes a locking member mounted within the tube bore for reciprocation longitudinally into and out of locking 85 position, spring means adapted normally to hold the member out of locking position, an actuating member operable from the end of the spindle and movable both longitudinally and rotatably, said actuating member 90 being movable longitudinally in one direction to move the body member into locking position, means adapted to hold the locking member releasably in locking position, said actuating member being thereafter rotatable to release said holding means, and key controlled means releasably holding said actuating member against rotation. 95
15. In a lock that includes a bolt adapted to be moved from extended to retracted position by rotation of a tubular spindle that 100 is operatively connected thereto, releasable means for holding said bolt against retractive movement that includes a locking member mounted within the tube bore for reciprocation longitudinally into and out of locking 105 position, spring means adapted normally to hold the member out of locking position, and a key-controlled lock cylinder movable bodily longitudinally in the direction of the 110 spindle axis to move the locking member into locking position against the action of said spring means. 115
16. In a lock, a bolt adapted to be reciprocated to and from extended position, means 120 for retracting the bolt and including a tubular rotary spindle arranged substantially axially perpendicular to the bolt and operatively connected thereto, a locking member within and movable longitudinally through 125 the bore of the spindle into and out of locking engagement with the bolt when said bolt is extended and adapted, when in such engagement, to hold said bolt against effective retraction, and selectively and independently 130

movable means at opposite ends of the spindle for moving the locking member into such locking engagement.

17. In a lock that includes a bolt adapted to be moved from extended to retracted position by rotation of a tubular spindle that is operatively connected thereto, releasable means for holding said bolt against retractive movement that includes a locking member mounted within the tube bore for reciprocation longitudinally into and out of locking position, a spring means adapted normally to urge and hold the member out of locking position, and means operable from either end of the spindle for moving said locking member into locking position against the action of said spring means.

18. In a lock that includes a bolt adapted to be moved from extended to retracted position by rotation of a tubular spindle that is operatively connected thereto, releasable means for holding said bolt against retractive movement that includes a locking member mounted within the tube bore for reciprocation longitudinally into and out of locking position, a spring means adapted normally to hold the member out of locking position, and selectively operable and independently movable means at opposite ends of the spindle for moving the locking member into and out of locking position.

19. In a lock, a bolt adapted to be reciprocated to and from extended position, means for retracting the bolt and including a tubular rotary spindle arranged substantially axially perpendicular to the bolt and operatively connected thereto, a locking member within and movable longitudinally through the spindle bore into and out of locking position, when the bolt is extended and adapted, when in such position, to hold said bolt against effective retraction, and a key-controlled member movable in substantial parallelism with the spindle axis and effective by such movement in one direction, to move said locking member into locking position and being thereafter movable in the opposite direction without moving said locking member out of locking position.

50 20. In a lock, a bolt adapted to be reciprocated to and from extended position, means for retracting the bolt and including a tubular rotary spindle arranged substantially axially perpendicular to the bolt and operatively connected thereto, a locking member within and movable longitudinally through the spindle bore into and out of locking position when the bolt is extended and adapted, when in such position, to hold said bolt against effective retraction, and a rotatable key-controlled member movable in substantial parallelism with the spindle axis and effective, by such movement in one direction, to move said locking member into locking position and being thereafter mov-

able in the opposite direction without moving said locking member out of locking position; said key-controlled member being further adapted, by its subsequent rotation, to free the bolt for retractive movement.

In witness that I claim the foregoing I have hereunto subscribed my name this 8th day of December, 1925.

JAMES M. WEAVER.
